UNITED STATES PATENT OFFICE.

GEORGE B. AMBLER AND HAROLD F. SHAW, OF LEOMINSTER, MASSACHUSETTS,
ASSIGNORS TO F. A. WHITNEY CARRIAGE COMPANY, OF LEOMINSTER,
MASSACHUSETTS, A CORPORATION OF MASSACHUSETTS.

FINISHING ARTICLES IN BASKETWARE.

1,424,972.

Specification of Letters Patent. Patented Aug. 8, 1922.

Application filed February 24, 1920. Serial No. 360,626.

To all whom it may concern:

Be it known that we, GEORGE B. AMBLER and HAROLD F. SHAW, citizens of the United States, and residents of Leominster, county 5 of Worcester and State of Massachusetts, have invented an Improvement in Finishing Articles in Basketware, of which the following description, in connection with the accompanying drawings, is a specification, 10 like characters on the drawings representing like parts.

This invention relates to basketry and more particularly relates to the finishing of the marginal portions of articles with rattan 15 or similar basket materials. The invention applies to articles constructed of or finished with such materials as have a certain stiffness as distinguished from freely flexible materials. Examples are so-called reed or 20 the woody part of the rattan, the heavier sorts of cane, willows or osiers, and the like, commonly associated with basketry and to substitutes therefor, such, for example, as paper reed. All these materials when woven 25 possess a certain stiffness and form what may be called a stake and strand fabric as distinguished from freely flexible textile fabrics.

Our invention may best be understood by 30 reference to the following description of an illustrative embodiment thereof taken in connection with the accompanying drawings wherein as an example of our invention we have shown the forward or well portion of a 35 baby carriage body having a marginal finish illustrating our invention. In these drawings:

Fig. 1 is a plan view of the finished body;

Fig. 2 is a partly broken elevation of the 40 partly finished body;

Fig. 3 is a section substantially on the line 3—3 of Fig. 1 showing a step in the construction of the margin; and

Fig. 4 is a similar section showing the 45 shaping of the marginal portion completed.

As an example of our invention we have herein shown a baby carriage body, the marginal portions of which are finished by hollow rolls of wicker fabric, the word "wicker" 50 being used in a somewhat extended sense to apply to the basketry materials referred to

above and their equivalents. This form of finish broadly is known in the art, it being effected by gradually shaping the stakes, usually those of the body fabric, to curved 55 form as the strands are interwoven therewith. This is of necessity a hand operation and requires considerable skill. The present invention contemplates forming these rolls in a convenient manner from a fabric which 60 may previously be woven in the flat and, if desired, by machine and in a manner not calling for technical skill in basket making.

In the drawings we have shown a baby 65 carriage body provided with a suitable supporting frame comprising the marginal frame portions 3 and a suitable body covering 5, preferably of wicker work. This body covering is conveniently formed from suitably shaped pieces cut from a sheet of 70 woven wicker fabric, such, for example, as a fabric of paper reed woven on a loom and marginally secured to the frame. The raw edges of the pieces of fabric 5 where they are secured to the frame may be covered and 75 hidden, for example, by the braid 7 made from similar reed.

Our invention more particularly relates to providing an article of this kind with a marginal finish similar in appearance to the 80 rolls which are formed by hand as an extension of the body fabric. In the example of our invention shown, a suitable strip 9 of wicker fabric, such as a machine woven 85 fabric of paper reed, and embodying stakes or warps 11 and strands or wefts 13, is applied and, as shown in Fig. 2, is secured to the marginal frame portion 3 conveniently in such a manner as to overlie the face of the fabric 5. That is, the strip 9 hangs down 90 over the face of the fabric 5 as it is attached. In the example shown the side frame 3 of the carriage is curved and the edge of the strip 9 is curved as it is attached to follow the curve of this frame and it is convenient 95 in this operation transversely to cup or bend the strip 9 more or less. In the case of paper reed this may be done without any special treatment of the fabric. In genuine reed the fabric would, of course, be first 100 suitably softened by soaking. The strip 9 is then rolled up lengthwise of the stakes 11

thereof and, in the example shown, reversely of itself in the manner indicated in Fig. 3, thus providing a hollow roll and the outer margin of the strip 9 is finally brought into contact with the opposite side of the frame piece 3 as shown in Fig. 4 and is secured thereto. The free end of the strip at the inner side of the frame piece may be covered in any suitable manner as by a braid 17 similar to the braid 7 or by the upholstery of the interior of the carriage. Fig. 4 represents the roll after it has been shaped to form but before it is finished by the application of the braids 21.

15 By a suitable manipulation of the strip the cross sectional area thereof may vary. For example, the rolls at the sides of the carriage in Fig. 1 taper toward the left and the left hand margins may be supported 20 directly on the frame pieces 3 and be covered over by the strips of reed braid 19. The major portion of the roll, however, is spaced from the marginal frame portion of the carriage. To provide a support for the right hand ends of these rolls a suitable block as 25 15 may be provided and secured to the frame members, which block 15 supports the ends of the strands 13 at the right hand end of the roll and receives the tacks or staples securing the braided strip 21 covering the raw end.

In the baby carriage herein shown as an example of the invention there are two side rolls and a front roll secured to corresponding intersecting frame portions. The block or support 15 is conveniently provided at the intersection of the two frame portions and supports the ends of both strips, the joint where the two strips meet being covered by the strip of braid 21, the front and side portions thus having the appearance of a continuous roll.

A marginal roll constructed in this manner by virtue of the stiffness of the wicker fabric maintains its hollow form. The appearance corresponds closely to the roll laboriously constructed by hand labor by a gradual shaping of the stakes of the body fabric of an article as the strands are interwoven therewith. In contrast to this method we are enabled to utilize a wicker fabric woven in the flat and conveniently by machine. Little or no skill is required to shape and bend this fabric to the hollow form indicated. In the example shown one margin is covered by the overhang of the roll itself and the other may be conveniently hidden by the upholstery of the interior of the baby carriage. The ends of the strip are covered with reed braid or similar material harmonizing with the material of the rolls themselves and providing a finish not only unobjectionable but ornamental in itself.

65 We have described in detail the partic-

ular embodiment of our invention as applied to the finish of the marginal portions of a baby carriage. The principles exemplified thereby which we claim as new and desire to secure by Letters Patent we shall express in the following claims.

Claims:

1. A method of finishing the margins of wicker articles comprising securing marginally of the article a strip of wicker fabric 75 to overlie the face thereof, reversely bending said strip and rolling the reversely bent strip into hollow form over the margin of the article the rolled strip being spaced from the margin of the article for at least 80 a major portion of its length and securing the opposite edge.

2. A method of finishing the margins of wicker articles comprising securing marginally of the article a strip of wicker fabric, 85 rolling said strip into hollow form, the rolled strip being spaced from the margin of the article for at least a major portion of its length and securing the opposite edge of the strip to the article. 90

3. A method of finishing the margins of wicker articles comprising securing marginally of the article a strip of wicker fabric, rolling said strip into hollow form, providing a support for an end of the strip, the 95 rolled strip being spaced from the margin of the article for at least a major portion of its length and securing the opposite edge of the strip to the article.

4. An article having a marginal frame portion and a body covering and a marginal roll comprising a transversely bowed strip of wicker fabric, the edges of which are secured to said marginal frame portion, the middle portion of the strip being spaced 105 therefrom for at least a major portion of its length.

5. An article having a marginal frame portion and a body covering and a marginal roll comprising a transversely bowed strip 110 of wicker fabric, the edges of which are secured to said marginal frame portion, one end of the strip having a support spacing it from said frame portion, and the middle portion of the strip being spaced therefrom 115 for at least a major portion of its length.

6. An article having two intersecting marginal frame portions and a body covering and a marginal roll extending along said portions and comprising a transversely bowed strip of wicker fabric extending along each such portion and having edges secured thereto and a support at the intersection of said portions for the ends of the strips, the middle portions of the strips 120 being spaced from said frame portions for at least a substantial portion of their length. 125

7. An article having two intersecting marginal frame portions and a body cov- 130

ering and a marginal roll extending along said portions and comprising a transversely bowed strip of wicker fabric extending along each such portion and having edges secured thereto, a support at the intersection of said portions for the ends of the strips, the middle portions of the strips be-

ing spaced from said frame portions for at least a substantial portion of their length, and a cover for the ends of the strips. 10

In testimony whereof, we have signed our names to this specification.

GEORGE B. AMBLER.
HAROLD F. SHAW.
